CONTAINER WITH INDIVIDUAL
INSCRIPTION

Samuel H. Born, Bethlehem, Pa.

Application February 23, 1949, Serial No. 77,779

2 Claims. (Cl. 229—8)

1

This invention relates to new and useful improvements in a package for candy, stockings or other similar small articles which can be given as gifts.

More particularly, the invention relates to an improved package for candy, stockings or other similar articles which is provided with an area which may be inscribed with an appropriate marking by the purchaser prior to giving the package to the person for whom it was purchased, so that the inscription will form a groove or impressed effect in the said area.

Still further, while the package of the present invention is especially well adapted as a container for candy it may be used equally well as a package for stockings or other small articles which can appropriately be given as gifts.

Another object of the present invention proposes providing an area of the package with a piece of metal foil or other similar material arranged in a manner to be impressed with the aid of any blunt pointed stylus, pen, pencil or any other writing instrument, with an appropriate marking befitting the occasion on which the gift is being given.

A further object of the present invention proposes padding the wall of the package upon which the piece of metal foil or other similar material is mounted in a manner so that the same may be more deeply impressed with the stylus, or other writing instruments, so that the marking will stand out more clearly.

It is the object of a modification of the present invention to form the metal foil or other similar material upon which the marking is to be impressed with appropriately located lines of perforations dividing off the center of the metal foil or other similar material so that the marking may be impressed within the divided off area to be torn from the remainder thereof and saved after the package has been emptied of its contents.

It is a still further object of the present invention to construct a novel package for candy, stockings or other similar small articles which is simple and durable and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a package for **55** easily read.

2

candy constructed in accordance with the present invention and as it appears when purchased.

Fig. 2 is a plan view of the package as it appears after being impressed by the purchaser.

5 Fig. 3 is an enlarged partial longitudinal sectional view taken on the line **3—3** of Fig. 1.

Fig. 4 is a plan view of the package constructed in accordance with a modification of the present invention, prior to being impressed.

10 Fig. 5 is an enlarged partial longitudinal sectional view taken on the line **5—5** of Fig. 4.

Fig. 6 is a similar view to Fig. 1, but showing a modified form of the invention.

15 The package for candy, stockings or other similar small articles, according to the first form of the invention shown in Figs. 1 to 3, includes a box **10** having a wall **11**. The wall **11** is preferably the top wall of the cover of the box **10**. The wall **11**, see Fig. 3, is comprised of a base of heavy cardboard **12** covered with an appropriately colored sheet of paper **13**. A padding **14** of any known type is interposed between the base **12** and the sheet of paper **13**. The top face of the sheet of paper **13** is imprinted with any desired indicia; such as the name of the maker of the enclosed chocolates or any other printed material. The entire box **10** is enclosed within a sheet of transparent material **15**; such as "cellophane."

20 Interposed between the sheet of paper **13** and the sheet of transparent material **15**, there is a piece of material **16** which may be impressed by the purchaser or other person with an appropriate marking prior to giving the package to the person for whom it was purchased. The piece of material **16** is preferably formed of a metallic foil and is secured in position by a layer of mucilage or other adhesive material **17**; however, the piece of metallic material **16** may be formed of any material which can be suitably impressed by a blunt 25 stylus, or the like, not shown.

25 In Fig. 1, the package is shown as it appears when purchased by the customer and in Fig. 2 the package is shown as it appears after being impressed with an appropriate Christmas greeting by the purchaser of the package. While the piece of metallic material **16** is shown applied to a package having a padded wall, this is by way of illustration only, as the piece of metallic material **16** may also be applied to a wall which is not padded. However, it has been found that if the wall to which the piece of metallic material **16** is applied is padded that the same may be more heavily impressed with the result that the marking stands out more clearly and can be more easily read.

In the modification of the invention shown in Figs. 4 and 5, the construction of the package 10' is similar to that shown in Figs. 1 to 3, except that the center area 16^a of the piece of metallic material 16' is divided off by lines of perforations 18. It is this center area 16^a of the piece of metallic material 16' which is to be impressed. The edges of the piece of metallic material 16', outside of the perforations 18, are secured to the top face of the sheet of paper 13 by the mucilage or other adhesive material 17' leaving the center area 16^a of the piece of metallic material 16' free of the sheet of paper 13.

With this construction, before or after the package has been emptied of its contents, the center area 16^a of the piece of metallic material 16', having the impressed marking, may be separated from the package along the lines of perforations 18 so that the marking may be saved by the receiver of the package.

In other respects this form of the invention is similar to the first form and like reference numerals identify like parts in each of the several views.

On the drawing, the sheet of metallic material is shown applied to boxes for containing chocolates, but this is by way of illustration only, as the present invention is equally well adapted to boxes for containing other small gift articles and may be applied to a wall of the box other than the top wall.

In Fig. 6, a container 19" is shown to be in the form of a box with a cover on which a metallic material 16" is held in position by any suitable means. In other respects this form of the invention is similar to the previous forms.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An inscription panel for a package having a top wall, comprising a padding covering the outer face of the top wall, a piece of impressible metal foil positioned on said padding so arranged and constructed that said padding provides a soft underlining for said piece of metal foil permitting a message to be impressed therein, lines

of perforations dividing off a center area of said piece of metal foil which is to be impressed with a message of greeting, and an adhesive securing the edge portions of said piece of metal foil outward of said lines of perforations to the adjacent face of said padding, whereby the message impressed center area can be separated from the remainder of the piece of impressible metal foil when the package is to be discarded.

- 10 2. An inscription panel for a package having a top wall, comprising a padding covering the outer face of the top wall, a piece of impressible metal foil positioned on said padding so arranged and constructed that said padding provides a soft underlining for said piece of metal foil permitting a message to be impressed therein, lines of perforations dividing off a center area of said piece of metal foil which is to be impressed with a message of greeting, and an adhesive securing 15 20 the edge portions of said piece of metal foil outward of said lines of perforations to the adjacent face of said padding, whereby the message impressed center area can be separated from the remainder of the piece of impressible metal foil 25 when the package is to be discarded, and a cover of flexible nonimpressible transparent material enclosing the box and having a portion extended across the exposed face of said piece of impressible metal foil, so arranged and constructed that 30 a message can be impressed on said piece of impressible metal foil through said cover and within said lines of perforations using a blunt instrument after which said cover will return to its normal position over said piece of impressible 35 metal foil to protect the impressed message.
